[57] CLAIM

The ornamental design for a garment hanger body, as shown and described.

DESCRIPTION

FIG. 1 is a perspective view of a garment hanger body showing my new design, the clamps being shown in the open condition;

FIG. 2 is an enlarged front elevational view thereof;

FIG. 3 is an enlarged top plan view thereof;

FIG. 4 is an enlarged right side elevational view

thereof, the left side being a mirror image thereof;

FIG. 5 is an enlarged rear elevational view thereof;

FIG. 6 is an enlarged top plan view thereof; and,

FIG. 7 is a perspective view thereof, the clamps being

shown in the closed condition.

FIG. 4

FIG. 1

FIG. 2

FIG. 3

FIG. 7
